WHEEL FLANGE LUBRICATING MECHANISM,
APPLICATION FILED JULY 31, 1913.

Patented July 21, 1914.

2 SHEETS—SHEET 2.

UNITED STATES PATENT OFFICE.

ROBERT H. SCROGGINS, OF VIENNA, VIRGINIA, ASSIGNOR OF ONE-HALF TO JOSEPH H. BRADLEY, OF WASHINGTON, DISTRICT OF COLUMBIA.

WHEEL-FLANGE-LUBRICATING MECHANISM.

1,104,322.

Specification of Letters Patent. Patented July 21, 1914.

Application filed July 31, 1913. Serial No. 782,342.

To all whom it may concern:

Be it known that I, ROBERT H. SCROGGINS, residing at Vienna, in the county of Fairfax and State of Virginia, have invented a new and Improved Wheel-Flange-Lubricating Mechanism, of which the following is a specification.

My present invention is an improved means for lubricating car wheel flanges, particularly the wheels of street cars to thereby materially facilitate the application of the grease to the wheel flanges for reducing the friction between the car wheel flanges and the curved track sections on which they run and also overcome the grinding noises incident in the ordinary running of the wheel flanges when rounding curves.

Another and important purpose of my present invention is the providing of an improved means for gradually applying the lubricant to the wheel flanges automatically and in such a manner that the grease is intermittently fed to the wheel flanges.

My present invention relates more particularly to that type of lubricating means disclosed in my copending application, Serial No. 769245, filed May 22, 1913, and one of the objects of this invention is to simplify the construction of my other lubricating means referred to and render the operating of feeding the lubricant the more positive and economical.

Another feature of my present invention lies in the improved construction of the grease applying or smearing nozzle brush that engages the wheel flange.

With other objects in view, all of which will be hereinafter referred to, my present invention embodies the peculiar and novel combination and arrangement of parts that will be hereinafter explained in detail, be specifically pointed out in the appended claims and illustrated in the accompanying drawings in which:

Figure 1 is a plan view of my improved wheel flange lubricating means, the parts being shown at the normal position, when the car trucks are traveling straight ahead. Fig. 2 is a side elevation of one of the lubricating cylinders and its coöperating lubricant applying devices, the nozzle with its flange wiping brush, being at the elevated or normal position. Fig. 3 is a side elevation of the outer end of one of the main cylinders, the lubricant applying devices being

shown at the operating or flange engaging position. Fig. 4 is a cross section on the line 4—4 on Fig. 3 looking in the direction of the arrow. Fig. 5 is a horizontal section taken substantially on the line 5—5 in Fig. 6. Fig. 6 is a transverse section taken on the line 6—6 on Fig. 5. Fig. 7 is a detail perspective view of the tubular rotary lubricant feed controlling valve, with its operating gear applied. Fig. 8 is a longitudinal section of the brush end of the distributing nozzle. Fig. 9 is a perspective view thereof. Fig. 10 is a detail perspective view of the casing for the brush and hereinafter specifically referred to. Fig. 11 is a detail cross section on the line 11—11 on Fig. 1. Fig. 12 is a detail cross section of the wiping head of the flange engaging brush, on line 12—12 of Fig. 9.

In my present construction of car wheel flange lubricating mechanism, I use a lubricant holding cylinder 1, mounted on the car truck in any suitable manner, one of such cylinders being located in advance of each of the car wheels as is clearly shown in Fig. 1.

Like in the construction shown in my copending application, each cylinder is arranged for being quickly recharged with heavy lubricant and has a screw cap 2 at one end through which the grease is entered into the cylinder. The cylinders in my present case each have the plunger 3 and spring 4 devices and the adjusting screw shaft 5 and hand-wheel 6 as in my other pending application, to provide for constantly forcing the thick lubricant contained within the cylinder, toward the aperture 7 through which the lubricant passes to the means for applying the same to the car wheel flange.

In my former construction, as shown in my copending application, the grease passes out through a laterally projected nozzle which coöperates with a cut-off gate automatically opened at predetermined times to permit of a discharge of the grease to the applying brush or to the flange wiper devices. From practical experience I have found that at times the supply of the thick grease is too fast and hence it does not develop all of the advantageous features desired in a mechanism of this kind.

In my present case I provide a supplemental grease holding cylinder or cup 8 for each of the main cylinders 1, which cup is

formed by boring out a block 9, which is riveted to the side of the ejecting end of the main cylinder 1. The block 9 has a diagonally disposed lubricant passage that opens up communication between the supplemental and the main grease holding cylinders, it being understood by reference to the drawings, that the supplemental cylinder is positioned at right angles to the main cylinder.

10 10 designates a tubular controlling valve of a size to snugly fit within the supplemental cylinder in which it is rotatably mounted and held to its seat by a cap nut 11 whose threaded flange 12 engages the threaded neck 13 of the said supplemental cylinder as shown. Cap nut 11 has a central bore to receive the shank 13 of the rotary controlling valve, the upper end of which has a gear 14 to which power is transmitted, in either direction, in the manner presently described.

15 The cylinder block 9 has a central laterally directed discharge 15 with which communicates the receiving end of a nozzle 16 that is swivelly connected to the block so that the discharging end 16^a of the said nozzle, (which projects forwardly in a plane parallel to the main cylinder) positions in line with the wheel flange to be lubricated therefrom. For conveniently connecting the nozzle, so it may swing vertically, to or from the wheel flange, the outer end of the block 9 is externally threaded as at 90, to receive the screw cap 17 centrally apertured to receive the inner end of the nozzle, the latter having a collar 19 to hold it in place.

20 Since in my construction of lubricating means, the plunger pushes against the heavy lubricant under a strong spring force the tendency of the lubricant is to flow freely out into and discharge from the nozzle. In the practical application of the lubricant feeding devices shown in my copending application at times there is a tendency for a continuous flow or ejection of the lubricant during the time that the car trucks round the curves.

25 By now referring to Fig. 5 it will be noticed that the single diagonally disposed lubricant outlet from the main cylinder and the several radial passages in the hollow rotatable controlling valve 10, are relatively so disposed to each other and to the single outfeed passage to the distributing nozzle, that at no time (no matter what the adjustment of the rotary valve may be) is there a direct passage from the main cylinder through the valve 10 to the distributing nozzle and by reason of the aforesaid arrangement of parts the lubricant is intermittently cut off or fed out to the distributing nozzle.

30 The distributing nozzle, (the special construction of which will be presently explained and which is pivotally supported to swing in the vertical plane,) is normally

held swung up away from the wheel flange X as is clearly shown in Fig. 2, by reference to which and Figs. 3 and 4 it will be noticed an upwardly extended arm 21 is secured to the top of the nozzle and the said arm includes an upwardly inclined member 22, which under certain adjustments, presently explained, engages a cam portion 23 in a wire guide 24 and is thereby caused to swing down and assume the "smearing" position shown in Fig. 3. One of the wire guides 24 is mounted on each end of a cross or link bar 25, that connects each part of lubricating mechanism as is clearly shown in Fig. 1. Each of the wire guides 24 is so positioned, relatively to the arm 21 on their respective nozzles, that the cam portions 23 of the said guides (under the normal or straightway running of the car) engage the arms 21 and hold the nozzles swung up away from the wheel flange, as shown in Fig. 2.

35 The cross or link bar 25 (see Fig. 1) is made in sections whose adjacent ends are connected by a coupling section 25^a, the ends of which are adjustably connected with the two end sections of the bar 25, by slot and bolt devices 25^b. The object in making the bar 25 in sections and lengthwise adjustable is to provide for a proper setting of the lubricating devices to bring them in the proper longitudinal alinement with the car wheels set either at a wide or narrow gage. The coupling section 25^a, centrally thereof, has a forwardly extended forked bracket 26, into which projects a roller bearing 27 on the lower end of a long bolt 28 pendent from the car platform, (see Fig. 11).

40 By connecting the coupling section 25^a with the pendent member 28, as shown and described, the lateral swing of the car platform or body, as the car approaches the curves, causes the link bar 25 to shift and in doing so, through the medium of the rack portions 31, on the said bar, that engage the gears on the stems of the hollow valves 10, rotates the said valves, one or more times, to thereby cause the radial lubricant passages to intermittently register with the feed outlets to the distributing brushes, it being understood that as some of the said radial 45 passages come into register with the feed channel to the brush or distributing nozzle, other of the said radial apertures come into register with the discharge opening from the main cylinder, it being also understood that 50 when the said radial passages in the tubular valve register with the said discharge opening from the main cylinder, the opening to the brush is cut out.

45 In my present construction of wheel flange lubricating means the lubricant brush carried by the nozzle and which under a wiping action applies the lubricant to the wheel flange, is composed of a pipe section 33 that screws into the outer end of the nozzle 55

proper, (see Fig. 8). In practice, the nozzle passage is say,—one inch in diameter, and the bore or passage of the pipe section at the delivery end is reduced to one-half an inch in diameter to prevent any possible excess amount of the lubricant passing to the brush device, the peculiar construction of which forms an essential feature of my present invention.

10 The brush device, comprises a large number of thin wire strands, preferably copper, arranged in opposing sets. These strands are first laid flatwise around the pipe section 16^a and are firmly secured at their inner 15 ends to the said pipe section by a sleeve of solder designated 34 on Figs. 8 and 9. The two opposing sets of strands are then divided and bent outwardly, then downwardly and back upwardly and their outer or free 20 ends bent back upon the upper side of the reducing nozzle section 33 to which the said ends are secured by soldering,—designated 36. To keep down an undue heating of the nozzle, the wire strands before they 25 are bent back and secured as in Fig. 12, are interlaced with asbestos or mineral wool 37 (see Fig. 12).

By twisting the wire strands and securing them to the pipe portions of the brush, a 30 substantially V shaped wiping head 38 composed of wire strands is provided, and the formation of the brush being such that when it is lowered to the wheel flange it straddles the said flange (see Figs. 3 and 5), in such a 35 manner that little or none of the lubricant being applied, is wasted. To hold the wire formed brush to shape and at the same time protect it from the weather, the said brush is inclosed by a casing 41 (see Fig. 10) 40 shaped to fit around the said brush.

From the foregoing description taken in connection with the drawings, the complete construction, the manner in which my improved wheel flange lubricating mechanism 45 operates and its advantages will be readily apparent to those skilled in the art to which it relates.

The construction and the coöperation of the parts permits of readily adjusting them 50 to adapt them for use on trucks of different gage, and since the shifting means, the link bar that joins with the oppositely disposed controlling valves is coöperatively connected with the swingable grease applying nozzles, it follows that the operation of dropping 55 the said nozzles to bring their brush ends onto the wheel flange and the setting of the controlling valves is simultaneous, as the car trucks round the curves, the said nozzles 60 and the valves being likewise reversely actuated when the car trucks leave the curve for the straightway track. While the arrangement of the parts shown and described disclose a preferred construction, the details 65 of construction shown may be readily varied

or modified without departing from my invention or the scope of the appended claims.

What I claim is:

1. A wheel flange lubricating mechanism that comprises the following elements in combination; a lubricant holding cup having an inlet and an outlet, means for normally forcing a lubricant into the said inlet, a valve device that controls the flow of the lubricant through the cup from the inlet to the outlet thereof, a wheel flange smearing member in communication with the outlet from the cup, a power transmitting member connected with the valve, means that joins said member with the car body for moving the said member laterally in reverse directions as the car body swings laterally when passing over curves to thereby shift the controlling valve to open and close the fluid passages between the inlet and outlet of the grease cup. 70 75 80 85

2. A wheel flange lubricating mechanism that comprises the following elements in combination; a lubricant holding cup having an inlet and an outlet, means for normally forcing a lubricant into the said inlet, a valve device that controls the flow of the lubricant through the cup from the inlet to the outlet thereof, a wheel flange smearing member in communication with the outlet from the cup, a power transmitting member connected with the valve, means that joins the said member with the car body for moving the said member laterally in reverse directions as the car body swings laterally when passing over curves to thereby shift the controlling valve to open and close the fluid passages between the inlet and outlet of the grease cup, said transmitting member being formed of sections, and means for longitudinally adjusting the said sections with respect to each other. 90 95 100 105

3. A wheel flange lubricating mechanism that comprises the following elements in combination; a lubricant holding cup having an inlet and an outlet, means for normally forcing a lubricant into the said inlet, a valve device that controls the flow of the lubricant through the cup from the inlet to the outlet thereof, a wheel flange smearing member in communication with the outlet from the cup, a power transmitting member connected with the valve, means that joins the said member with the car body for moving the said member laterally in reverse directions as the car body swings laterally when passing over curves to thereby shift the controlling valve to open and close the fluid passages between the inlet and outlet of the grease cup, and means carried by the 110 115 120 125 transmitting member for setting the smearing member into and out of engagement with the wheel flange as the controlling valve is shifted.

4. In a wheel flange lubricating mecha- 130

nism, a lubricant container having a discharge through which the lubricant is ejected, means for normally forcing the lubricant through the said discharge, a supplemental grease holding cylinder or cup in communication with the said discharge, the said cup having an outlet, a smearing member in communication with the said outlet, a tubular valve rotatably mounted within 10 the grease cup, said valve having radial apertures adapted to be alternately brought into communication with the inlet and outlets of the grease cup, means connected with the said rotatable tubular valve and with 15 the car body whereby to automatically shift the said valves as the car truck passes onto and from the curved trackway sections.

5. In combination a lubricant holding cylinder having a discharge means that coöperates with the cylinder for creating a continuous force feed of the lubricant through the said discharge, a pivotally supported smearing member adapted to swing in the vertical plane and to drop against the wheel 25 flanges, a lubricant feedway in constant communication with the smearing member, a valve coöperatively connected with the said feedway for controlling the passage of the grease therethrough to the smearing 30 member, and operative connections between the car body and the valve and the smearing member for shifting the said smearing member and the valve at times when the wheel truck enters and passes over curved 35 track sections.

6. A car wheel lubricating mechanism of the character stated in combination with a source of grease supply, connections between the car body and the supply for effecting 40 a flow of the said supply as the car wheels pass onto a curved track section, of a smearing member in communication with the said source of grease supply, the said smearing member including a smearing head shaped 45 to fit over the wheel flange and composed of a series of copper wire strands bent up and shaped to form the said head devices.

7. A car wheel lubricating mechanism of the character stated in combination with a source of grease supply, connections between the car body and the supply for effecting a flow of the said supply as the car wheels pass onto a curved track section, of a smearing member in communication with the said source of grease supply, the said smearing member including a smearing head shaped to fit over the wheel flange and composed of a series of copper wire strands bent up and shaped to form the said head devices, and a substantially non-heat conducting substance 60 interwoven with the said wires.

8. A car wheel lubricating mechanism of the character stated in combination with a source of grease supply, connections between the car body and the supply for effecting a flow of the said supply as the car wheels pass onto a curved track section, of a smearing member in communication with the said source of grease supply, the said smearing member including a smearing head shaped 70 to fit over the wheel flange and composed of a series of copper wire strands bent up to shape to form the said head devices, a substantially non-heat conducting substance interwoven with the said wires, and a jacket 75 shaped to fit over the smearing member and the brush head.

9. In a car wheel lubricating mechanism of the character stated, the combination with a source of lubricant supply, means for effecting the flow of the lubricant as the car wheels pass on to a curved track, of a smearing member in communication with the source of grease supply, the smearing member including a head portion shaped to fit 85 over the wheel flange and composed of an inner or body portion of pliable material and an outer or casing portion of sheet metal.
